UNITED STATES PATENT OFFICE

163,262

DISH

Frank Dilena, San Francisco, Calif.

Application December 11, 1950, Serial No. 13,378

Term of patent 3½ years

(Cl. D44—15)

To all whom it may concern:

Be it known that I, Frank Dilena, a citizen of the United States of America, resident of 160 Wood Street, city and county of San Francisco, and State of California, have invented a new, original, and ornamental Design for a Dish, of which the following is a specification, reference being made to the accompanying drawings, forming a part thereof:

Fig. 1 is a front elevational view of a dish showing my new design;

Fig. 2 is a side elevational view; and

Figs. 3 and 4 are, respectively, top and bottom plan views thereof.

I claim:

The ornamental design for a dish, substantially as shown.

FRANK DILENA.
